WITNESS:

W. D. Dell.

INVENTOR,
Albert J. Baum,

BY
John Stewart,
ATTORNEY.

UNITED STATES PATENT OFFICE.

ALBERT J. BAUM, OF NEW YORK, N. Y., ASSIGNOR TO ALBERT WANNER, JR., OF NEW YORK, N. Y.

MANUFACTURE OF CHAIR-SEATS.

1,224,891.

Specification of Letters Patent.

Patented May 8, 1917.

Application filed November 19, 1915. Serial No. 62,340.

To all whom it may concern:

Be it known that I, ALBERT J. BAUM, a citizen of the United States, residing at New York city, in the county of New York 5 and State of New York, have invented certain new and useful Improvements in the Manufacture of Chair-Seats, of which the following is a specification.

This invention relates to the manufacture 10 of chair seats and particularly to chair seats whose seats proper are composed of already-woven or so-called "machine" caning or other flexible sheet material, and it has for its object to simplify and reduce the cost 15 of assembling the seats proper with their frames and to provide a more durable and substantial seat than that which results from the method now commonly practised and consisting in routing or grooving one plane 20 surface of the frame and binding the margin of the seat proper therein by the use of a strip of cane reed superimposed on such margin and jammed or wedged therewith into and cemented in such groove.

25 In the accompanying drawings,

Figure 1 is a plan view of the improved seat; and

Fig. 2 is a transverse sectional view thereof.

The ring or frame of a chair of the bent- 30 wood type is indicated at *a*, being as usual a suitable length of wood bent into continuous form and having its ends suitably joined together.

It is surmounted by the ring-shaped portion *e*, which in the illustrated example is formed separately from frame *a* and is secured upon it by brads *b*; a rabbet *b* is produced, the portion *e* being of smaller diameter than that marked *a*.

40 *e* indicates the seat-proper, formed of any suitable flexible sheet material, but in the present instance being illustrated as already-woven or "machine" caning. The material of the seat-proper *e* is cut primarily to substantially the same contour as the portion *e*, though it is somewhat larger in diameter than the same.

45 *d* is a continuous ring or frame, formed of a suitable length of bent-wood having its ends suitably secured together; its cross-

section is such that at its inner circular side and its under side it conforms substantially to the shape of the rabbet *b*.

Portion *e* and ring *d* are formed with external and internal (respectively) grooves 55 as shown, to receive a hoop or band *o*, preferably of heavy wire, brought into registry therewith.

To form the seat, the material of the seat-proper *c* is superimposed upon the portion 60 *e*, whereupon the ring *d* being superimposed upon the marginal part of the seat-proper *c* the ring is forced downward over and around the portion *e* and the marginal portion of the seat-proper *c*, and the hoop or 65 band *o* forced into place, seating directly in the groove of one member *e*—*d* and pressing said marginal portion into the other groove, thus clamping the latter in place. When the parts have been thus established, 70 ring *d* may be held by the brads *f* or other securing means, shown in Fig. 2 as driven vertically through the ring into the frame.

By forming seats in this manner, the seat 75 proper is not only drawn to the desired degree of tautness without the employment of other means than parts of the seat itself, but once the joint is formed the seat proper is held with absolute security around its margin, remaining permanently uniformly 80 taut in its whole area.

Having thus fully described my invention, what I claim as new and desire to secure by Letters Patent is:

1. The herein described chair seat including concentric endless frame members, a seat proper formed of a piece of flexible sheet material, said piece being extended over, and being in a substantially uniformly taut state as to the whole area of, the inner frame 85 member and having its marginal part extended between said frame members, and a hoop interposed between said members in concentric relation thereto and clamping the marginal part of said seat proper in place, 90 said hoop having a continuous groove-interlock with each of said members.

2. The herein described chair seat including concentric endless frame members, a seat proper formed of a piece of flexible sheet 100

material, said piece being extended over, and being in a substantially uniformly taut state as to the whole area of the inner frame member and having its marginal part extended and continuously clamped between said frame members, said members having opposed continuous grooves, and a hoop en-

gaging in one of said grooves and pressing the marginal part of the seat proper into the other groove and thus interlocking said members. 10

In testimony whereof I affix my signature.

ALBERT J. BAUM.
